Attorney, Agent, or Firm—Banner & Allegretti, Ltd.**[57] CLAIM**

The ornamental design for an electronic computer, as shown and described.

DESCRIPTION

FIG. 1 is a top, front and right side perspective view of an electronic computer showing my new design according to a first embodiment thereof;

FIG. 2 is a front elevational view thereof;

FIG. 3 is a rear elevational view thereof;

FIG. 4 is a top plan view thereof;

FIG. 5 is a right side elevational view thereof;

FIG. 6 is a front elevational view thereof in a closed position;

FIG. 7 is a right side elevational view thereof in the closed position;

FIG. 8 is a bottom plan view thereof;

FIG. 9 is a left side elevational view thereof;

FIG. 10 is a top plan view thereof in the closed position;

FIG. 11 is a top, front and right side perspective view thereof with the CD-ROM case being open;

FIG. 12 is a top, front and right side perspective view of an electronic computer showing my new design according to a second embodiment thereof;

FIG. 13 is a front elevational view thereof;

FIG. 14 is a rear elevational view thereof;

FIG. 15 is a top plan view thereof;

FIG. 16 is a bottom plan view thereof;

FIG. 17 is a left side elevational view thereof;

FIG. 18 is a right side elevational view thereof;

FIG. 19 is a front elevational view thereof in a closed position;

FIG. 20 is a right side elevational view thereof in the closed position;

FIG. 21 is a top plan view thereof in the closed position; and,

FIG. 22 is a top, front and right side perspective view thereof with the CD-ROM case being open.
